TUBE CLEANER

Cecil M. Griffin, Pittsburgh, Pa.

Application May 23, 1936, Serial No. 81,430

4 Claims. (Cl. 15—104.06)

This invention relates to tube cleaning devices, and more particularly to a tube cleaner of the type adapted for use in the cleaning of steam condensing tubes wherein the cleaning tool is propelled through the tube to be cleaned by fluid under pressure. The invention constitutes an improvement over cleaners of the general type shown in my prior patent, No. 1,814,752, dated July 14, 1931.

10 Tube cleaners of the type to which the present invention relates generally comprise a body having a number of resilient scraper elements supported thereon, these scraper elements being inclined to the transverse axis of the body. The 15 scrapers which are slightly resilient engage the inner wall of the tube and remove sediment and encrusted matter. If there is solid matter too firmly encrusted upon the inner wall of the tube or if the tube has some irregularity, the scraper 20 units can yield to clear such obstruction.

While a tube cleaner as shown in my prior patent has proven highly satisfactory, my present invention provides a cleaning tool having both right and left hand inclined scrapers. The opposite 25 inclination of the scrapers prevents rotation of the cleaner in the tube. Moreover, the invention contemplates an arrangement wherein scrapers are distributed along the body of the tool, whereas in my former patent they encircle 30 the body at one place. This arrangement keeps the tool in better alignment and also provides better clearance against clogging. The invention further contemplates a construction wherein two 35 scraper blades are attached together as an integral unit so that one supports the other, obviating the necessity of a rigid connection of the scraper to the body, or to some auxiliary support on the body, thus simplifying the construction and enhancing the ruggedness of the cleaner.

40 The present invention, therefore, provides a cleaner which is highly efficient, can be cheaply manufactured, and is sufficiently rugged to withstand the hard usage to which devices of this type are subjected, particularly when being propelled from the end of a tube at relatively high 45 velocity against a metal plate or back wall. The present invention, moreover, provides a tube cleaner having scraper units of unique construction, the arrangement being such that the cleaner 50 can be easily assembled.

This invention may be readily understood by reference to the accompanying drawing, in which

55 Figure 1 shows a side elevation of a tube cleaner constructed in accordance with the present invention;

Figure 2 is an end elevation looking at the rear end of the cleaner shown in Figure 1, part of the end disk being broken away;

Figure 3 is a transverse section in the plane of line III—III of Figure 1;

Figure 4 is an end view of one of the scraper units;

Figure 5 is an exploded view showing the elements in the order in which they are assembled to form the complete structure illustrated in Figure 1; and

Figure 6 is a perspective view showing one of the scraper units.

Referring more particularly to the drawing, 2 designates a central stem member or core. It is 15 preferably square or non-circular in cross section and has an intermediate twist of about 45° between its ends, as indicated at 2^a. A circular head member 4 is fitted onto the portion 3, and the portion 3 is riveted over as indicated in Figure 1 and Figure 2 to firmly secure the head member and the stem member. Positioned on the stem member is a plurality of scraper elements 5, 6, 7 and 8. All of the scraper elements are of identical construction. One of these elements is shown in detail in Figures 4 and 6. Each of the scraper elements comprises a U-shaped body 9 formed of flat spring metal, the U-shaped body having two leg portions 9^a and 9^b. The connecting part of the body is designated 9^c and this connecting part is provided with a square or other non-circular central hole 10. The metal surrounding the hole is pressed or bulged outwardly from the normal plane of the metal, as indicated at 10^a. This bulge serves an important purpose in reinforcing the scraper and preventing it from bending on a line drawn across it through the hole. Without such bulge the scraper would be weakened across its middle. The free ends of the arms 9^a and 9^b of the U-shaped body are bent inwardly as indicated at 11 and then flare transversely outwardly, providing scraper portions 12. The outer edges of the scraper portions 12 are curved, these edge portions being designated 13. The curvature of this edge of the scraper corresponds to the curvature of the inside of the tube in which the cleaner is adapted to be used. The arm portions 9^a and 9^b of the U-shaped body are of reduced width from the central hole 10 toward the inwardly bent portion 11, this portion of minimum width being designated 14.

The two blade portions 12 of the scraper elements are both inclined in the same direction from a plane transverse to the arms of the U- 55

shaped body. By reason of this, one of the scrapers has a left hand pitch or slope with reference to an axis running through the center of the hole 10 while the other has a right hand 5 pitch or slope.

In the tube cleaner assembly, scraper element 8 is placed on the stem 2 against the head 2^b, the stem passing through the central hole 10 thereof. Following this scraper element, short spacer element 18 is placed on the stem 2, and this is followed by scraper element 7 which is followed by a long spacer 17 which is about double the length of spacer 18 and in turn by a scraper element 6, short spacer 16, the last scraper element 5, and 10 finally the second long spacer 15. After the spacer 15 is in place the head piece 4 is placed on the stem and the end of the stem is then upset or riveted, the countersunk portion of the head 3 being provided for this upsetting of the 15 end of the stem.

In the assembly, it will be noted that the two scraper units 5 and 6 are at right angles to each other as are also the two scraper elements or units 7 and 8. The scraper combination 5-6 25 is turned 45° out of phase with the combination 7-8 by reason of the twist at 2^a in the stem. The non-circular stem 2 engaging in the non-circular openings 10 holds the scrapers from relative rotation. It will be seen that scraper unit 6 overlaps scraper unit 5 and scraper unit 8 overlaps scraper unit 7, and that in this overlapping arrangement the base portion 9^a of the scraper elements or units 5 and 7 is between the two arms 9^a and 9^b of the succeeding scraper 30 element. The arms 9^a and 9^b of the elements 6 and 8 are clear of the base portion 9^a of the elements 5 and 7 so that all the scraper elements 35 can spring or yield radially inwardly when pressure is applied to the edges of the blades.

The cleaner assembly is inserted in the tube to be cleaned with the end having the disk 4 aftermost. As it is pushed into the tube, the inner wall of the tube will be engaged by the edges 13 of the blades 12. The blades will be 40 pressed or forced inwardly, but the resilience of the metal of which the scraper elements are made springs them out against the inner walls of the tube with sufficient pressure to provide the necessary cleaning action. At the same time, each 45 blade can move radially inwardly sufficient to clear such immovable obstructions as are normally encountered in the cleaning operation which these cleaners are adapted to perform.

Each blade 12 extends through an arc somewhat greater than 45°. By reason of the units 55 7 and 8 being out of phase with the units 5 and 6, the entire inner wall of the tube will be adequately scraped.

Since all of the scraper elements are the same, 60 the structure or cleaner can be very cheaply manufactured. The structure is easy to assemble, it merely being necessary to assemble the scraper elements on the stem 2 with the spacer elements therebetween and with each scraper 65 element turned 90° to the preceding one. The assembly is such that the arms 9^a provide sufficient rigidity to urge the edges 13 of the blades into contact with the inner surface of the tube to be cleaned, but also provide enough spring 70 so that the scrapers can flex inwardly when an immovable obstruction is encountered.

As before stated, by reason of the fact that both blades of each scraper element are inclined in the same direction with reference to a 75 transverse plane through the body, this gives

them the effect, when considered with reference to the longitudinal axis of the body as having an inclination or pitch opposite each other. That is to say, one scraper tends to impart a right hand threading or rotational movement to the body 5 while the other tends to impart a left hand threading or rotational movement. By reason of the metal being cut away at 14, the blade portions can be bent to shape more effectively and without causing the metal to crimp or buckle, 10 which would be the case if the arms were of uniform width throughout. Moreover, the structure can be more effectively formed by putting the reverse bend 11 into the metal just back of the scraper blade. The reverse bend also provides room for the dirt scraped from the tube to get away and thus prevent clogging of the 15 scraper.

While I have specifically illustrated and described one embodiment of my invention, it will 20 be understood that various changes and modifications in the detailed construction thereof may be made.

I claim:

1. A tube cleaner comprising an elongated 25 body member of non-circular cross-section, a plurality of substantially U-shaped scraper elements having non-circular holes therethrough threaded onto said body member, spacers separating the several scraper elements, said body 30 member being provided with means for retaining the scrapers and spacers against longitudinal movement, said scraper elements having blade portions on the free ends thereof, the scraper elements being arranged on the body in such 35 manner that some of the elements overlap other elements, the elements which overlap the other elements being set 90° around from the elements which they overlap, said elements being arranged in groups, said non-circular body member 40 being twisted at an angle of less than 90° intermediate two groups whereby the scraper elements of one group are out of phase with those of another group, the elements being formed of resilient spring metal.

2. A scraper member for condenser tube cleaners comprising an integral sheet metal stamping of general U-shape form with the outer free end of each arm of the U-shaped piece being turned outwardly perpendicular to the plane of 50 the sheet metal arm of the U-shaped member and at an inclination to a plane which is at right angles to the longitudinal axis of the U-shaped member, such outwardly turned portions forming scrapers, the two scrapers of the member 55 being parallel.

3. A scraper member for condenser tube cleaners comprising an integral sheet metal stamping of general U-shape form with the outer free end of each arm of the U-shaped piece being 60 turned outwardly perpendicular to the plane of the sheet metal arm of the U-shaped member and at an inclination to a plane which is at right angles to the longitudinal axis of the U-shaped member, such outwardly turned portions 65 forming scrapers, the two scrapers of the member being parallel, the metal at the base of the scrapers being bent inwardly in a trough-like form which is wide and deep at one end of the scraper and shallower and narrower at the other 70 end of the scraper.

4. A condenser tube cleaner comprising a central body member having a pair of U-shaped elements non-rotatably carried thereon, one of the elements being longitudinally spaced from 75

the other a distance such that the terminals of the arms of one of the elements come between the terminals and base of the other element, one element being angularly displaced 90° on the body with respect to the other, each of the U-shaped elements being an integral sheet metal structure having a base, arms and terminal portions at the free ends of the arms, the terminal

portions being turned outwardly with respect to the body member to form a scraper, the turned-out portions being set in a common plane which is at an angle to a plane passing at right angles through the longitudinal axis of the U-shaped element.
